Des. 190,611
Patented June 13, 1961

190,611

ASH TRAY OR THE LIKE

John M. Lindley, 1565 Madison St., Oakland, Calif.

Filed Oct. 2, 1959, Ser. No. 57,777

Term of patent 14 years

(Cl. D85—2)

I claim:

The ornamental design for an ash tray or the like, substantially as shown.
